FIG. 10

FIGURE 1 is a front perspective view of a combined water cooler and cabinet embodying my new design;

FIG. 2 is a front elevational view thereof;

FIG. 3 is a top plan view thereof;

FIGURE 4 is an elevational view taken from the right end thereof, the left end being a mirror image of the end shown;

FIGURE 5 is a front perspective view of a modified form of the cabinet shown in FIGURE 1;

FIGURE 6 is a front elevational view of FIGURE 5;

FIGURE 7 is a top plan view of FIGURE 5;

FIGURE 8 is an elevational view taken from the left end of FIGURE 5;

FIGURE 9 is a front perspective view of another modified form of the combined water cooler and cabinet shown in FIGURE 1;

FIGURE 10 is a front elevational view of FIGURE 9;

FIGURE 11 is a top plan view of FIGURE 9; and

FIGURE 12 is an elevational view taken from the left end of FIGURE 9.

The rear walls not shown are conventionally plain.

The dominant features of my design reside in the portions shown in full lines.

I claim:

The ornamental design for a combined water cooler and cabinet, substantially as shown and described.
